Primary Examiner — Kevin K. Rudzinski*Assistant Examiner* — Kimberly Barnes(74) *Attorney, Agent, or Firm* — Perry Saidman, LLC(57) **CLAIM**

The ornamental design for a tile, as shown and described.

DESCRIPTION

The sole FIGURE is a top view of a tile showing my new design.

Depth forms no part of the claimed design. The grey shading represents the two-dimensional layout of the tile, and does not indicate color or contour.
